CLAIM

The ornamental design for an engine starter, as shown and described.

DESCRIPTION

FIG. 1 is a top view of an engine starter according to the present invention. The broken line showing throughout the drawing disclosure is included for the purpose of illustrating environmental elements only and forms no part of the claimed design;

FIG. 2 is a side elevation view of an engine starter according to the present invention;

FIG. 3 is a bottom view of an engine starter according to the present invention;

FIG. 4 is a left end elevation view of an engine starter according to the present invention; and,

FIG. 5 is a right end elevation view of an engine starter according to the present invention.

The back side elevation of the starter design according to the present invention would be a mirror image of FIG. 2.

FIG. 1
